UNITED STATES PATENT OFFICE.

HUGH COTTER, OF BURLINGTON, CANADA.

BAG-SUPPORTING DEVICE.

SPECIFICATION forming part of Letters Patent No. 544,461, dated August 13, 1895.

Application filed April 11, 1895. Serial No. 545,287. (No model.)

To all whom it may concern:

Be it known that I, HUGH COTTER, a citizen of Canada, residing at Burlington, in the county of Halton, in the Province of Ontario, 5 Canada, have invented a new and useful Bag-Supporting Device, of which the following is a specification.

My invention relates to a bag-supporting device for use while filling, in which a metallic hopper, preferably oval to suit the shape of a bag, is suspended from an apertured vertical board at a convenient distance from the ground floor to suit the requirements of filling into the bag, which can be easily and quickly 10 adjusted to and around the body of said hopper and held in desired position, the objects of my invention being, first, to provide means whereby a bag or sack may be held in a steady and open position while being filled; second, 15 to afford facilities for the proper and rapid attaching of the bag to open position and the detaching of said bag without wear, tear, or injury of any kind, and, third, to allow the hopper with bag to be placed in a low position 20 from the floor and gradually raised at pleasure to any reasonable height for filling purposes. I attain these objects by the device 25 illustrated in the accompanying drawings, in which—

Figure 1 is a front elevation of my improved bag-supporting device with bag, the metallic hopper being in section and the front part of the bag being torn away to just below said hopper, in order to show the two upper side edges 30 of the bag secured in the two side bag-clamps by means of pins and also more fully the said hopper. Fig. 2 is a side elevation of the same, showing how the metallic hopper is suspended from and in line with a vertical board by 35 means of a three-ended hook, and Fig. 3 is an enlarged front elevation of the right-hand side detached bag-clamp, these views embodying my invention. Fig. 4 is an enlarged detailed 40 sectional view of one of the clamps or clips F in a plane at right angles to the detailed view, Fig. 3, to show the taper form of the opening, the bag-fastening pin H being in dotted lines.

Similar letters and figures refer to similar parts throughout the several views.

The metallic hopper A, which is preferably constructed of an oval shape to conform to the shape of a bag, is provided at its rear with

two apertured ears or lugs C, riveted to said hopper a certain distance apart to allow the same to be suspended in a proper manner 55 from the vertical board B by means of the three-ended hook D. The two lower right-angle ends of this hook enter and pass through the said ears, and the upper hooked end 2 passes through any one of the series of apertures 3, which the vertical board has at various distances from the ground, in order to lower and raise the hopper and its bag, when necessary, while filling.

The hopper is provided with two bag-clamps 65 F, one on each side and riveted thereto, these clamps being provided with an upper lip or hook 4, securing the same to the hopper more permanently. These clamps have concave recesses 5, the inner halves of which are corrugated concave recesses, as at 6, and the said recesses extended upward, as at 7, and continued downward, as at 8, for insertion of upper side ends of bag and fastening purposes. In order to fill the bag or sack E the open end 70 is drawn up over the lower taper end of said hopper until the upper side ends of said bag reach the said bag-clamps F, then through the lower openings 8 and concave recesses 5 into the upper openings 7. At this time a tapered 75 pin or plug H is inserted in said recesses 5 and 6 and the bag is held in position in and against the corrugations 6 in said recesses 5 and 6 of clamps F. The openings 8 are wide at the lower end and verge toward the center of recesses 5 and 6 to admit the bag freely. These corrugated bag-clamps are a very important 80 element in my invention, as they prevent any possible slipping of the bag from position while being filled. Also, the peculiar shape 85 and construction of the continuous recesses 5 and 6 and openings 7 and 8 in the clamps are important features, as they render the attachment and detachment of the bag a very easy matter in conjunction with the tapered pin 90 H. To render this clamp more operative, the recesses 5 are slightly tapered from the front side to conform to the taper of the said pins which must enter their openings from the front side of the device, as delineated in Fig. 2 of 95 the drawings.

The utility of the series of apertures 3 in vertical board B, previously referred to, will be obvious. When the upper part is lowered

produce is more easily put into the bag without dust or abrasion, and especially in the case of good apples, which may be put in and the hopper with bag raised by degrees, this being an important element. This said board

B may be placed in close proximity to any

wall or may be placed in any convenient or

suitable position, as the requirements of the

operation of filling bags may present.

It will not be necessary to define the exact depth or the front or rear taper of the hopper. These tapers may be of an angle best adapted to the requirements of the case. Also, the important bag-clamps F may, if deemed expedient, be fastened in a higher or lower position on the hopper.

What I claim as my invention, and desire to secure by Letters Patent, is—

1. In a bag supporting device the combination of a metallic oval hopper, provided with, and having secured thereto, the bag clamps F, having upper lips 4, to hook over the upper edge of said hopper, and circular taper openings 5, the inner halves of which have corrugations 6, the upper and lower continuous openings 7, and 8, the said openings 8, wider at the lower end to admit the edges of the bag freely, and the taper pins H, to hold edges of

the bag in said openings of clamp, substantially as described and set forth.

2. In a bag supporting device, the combination of the hopper provided with the rigid clamps F, having lip 4, and circular taper openings 5, the inner parts of which are corrugated as at 6, and the continuous openings 7 and 8 to admit the upper edges of bag freely, the bag holding taper pins H, the two ears C, secured a certain distance apart to the upper rear part of said hopper, for the insertion of lower end of hanging hook D, the upper end 40 of which is hooked in one of the series of apertures 3, in vertical board B, to adjust said hopper with bag E, to different heights from the floor, substantially as described and set forth.

3. The bifurcated clamp F, having the jaws therefor formed to present the taper opening comprising the corrugated concave recess 6, and the concave recess 5, and the hooked upper end 4, in combination with the tapering pin, and the oval hopper A, substantially as described.

HUGG COTTER.
